Patented Feb. 19, 1918.

UNITED STATES PATENT OFFICE.

NAPOLEON B. DOUGLASS, OF BERKELEY, CALIFORNIA.

WALL-BED.

1,256,667.

Specification of Letters Patent. Patented Feb. 19, 1918.

Application filed February 12, 1917. Serial No. 147,992.

To all whom it may concern:

Be it known that I, NAPOLEON B. Douglass, a citizen of the United States, residing at Berkeley, in the county of Alameda and State of California, have invented new and useful Improvements in Wall-Beds, of which the following is a specification.

This invention relates to wall beds and pertains especially to a reversible wall bed of the type illustrated in Patent #892,668, 10 Chas. R. Jordan, dated July 7, 1908.

In the patent above referred to there is a centrally pivoted panel carrying a bed on one side and reversible in an opening in the wall, 15 so as to carry the bed from a concealed position in the closet to an open position in the room; the panel in either of its reversed positions entirely closing the opening.

A centrally pivoted reversible panel of the patented type above requires a depth of recess or closet at least equal to one-half the width of the panel. In modern apartment house construction where space is particularly valuable and closets must be as shallow as possible, this type of centrally pivoted panel bed is often undesirable. For example, with a 54 inch panel the closet must be at least 26 inches deep. This is in addition of course to the fact that the closet cannot be entered when the panel is in either of its reversed positions, particularly when the bed is in the room, except by lifting up the foot of the bed and moving it to an ungainly angle. Even then the space that is afforded is insufficient for an adult to pass comfortably.

The present invention, aside from providing a special form of hanger for the turnable panel (which in the present case is not strictly reversible) is designed to provide a means by which the panel when in one position will entirely close the opening and conceal the bed behind it, and when in the opposite position will present the bed for use in the room, and at the same time leave sufficient space between one side of the panel and the adjacent panel for ingress and egress to and from the closet space behind the panel. Furthermore, the present structure will allow a very much shallower recess or closet than was possible in the former patented structure.

These results are accomplished by a special method eccentrically mounting the panel, as will more fully hereinafter appear.

Having reference to the accompanying drawings—

Fig. 1 is a front elevation of a panel in closed position.

Fig. 2 is a cross section on line 2—2 of 60 Fig. 1.

Fig. 3 is a detail of the upper pivot.

Fig. 4 is a cross section of same.

Fig. 5 is a detail of the lower pivot.

Fig. 6 is an elevation in partial section 65 of the same.

A is a panel fitting an opening in the wall 2. This panel when it stands flush with the opening presents to the room a continuation of the wall and may be ornamented or not, 70 as desired. The opposite side of the panel is adapted to carry a bed frame 3 mounted in the usual manner, to swing from a vertical inoperative position to a horizontal position for use when the panel is reversed. 75 The panel is of a width and height corresponding to the size of the bed frame employed. Where the bed frame is that of a double bed the panel is preferably 4 ft. 6 inches in width. The panel turns on vertical pivots 4—5. Instead of being centrally pivoted this panel is pivoted about one-third of the width of the panel on one vertical edge thereof, and instead of being pivoted in the plane of the panel the pivots are sufficiently outside the plane of the panel so that the latter may stand flush with the wall when the bed is in the closet and when the panel is turned on the pivots it will stand forward of its former position and parallel 80 therewith and parallel with the wall, as shown in dotted lines, Fig. 2.

By this method of eccentric pivoting there is a considerable space left to one side of the panel and bed and the adjacent jamb as is seen on the left of Fig. 2; this opening in a 4 ft. 6 inch bed being approximately 18 inches, which is sufficient for ingress and egress.

Also by this method of eccentric pivoting, 100 a very shallow closet can be employed; the width of the closet being not greater than 21 inches with a double bed, and a 54 inch panel.

The upper pivots 5 comprise two plates 105 7—8; plate 7 being attached to the upper jamb and having an off-set pintle 9 to fit in the socket in plate 8, which latter is attached to the upper edge of the panel. The lower pivot 4 comprises a plate 10 secured to the 110

under-edge of the panel and having an off-set pintle member 11, with a conical point seating into a screw-threaded socket 12 which is adjustable in plate 13, secured to the floor. The two pintle members 9 and 11 lie entirely outside of the plane of the panel; the amount of either off-set depending on the space between the two positions occupied by the panel when in closed or open position.

Having thus described my invention, what I claim and desire to secure by Letters Patent is—

1. In a wall bed, the combination of a panel turnable in an opening in the wall, said panel being pivoted to one side of its center but substantially remote from either vertical edge, said panel when closed lying in the plane of and closing the opening, with its pivots lying outside of the plane of the panel and in a vertical line so that when the panel is swung through an arc of 180° it presents an opening to one side of the panel sufficient for passage through the

opening, and an article of furniture carried on the panel of less width than the maximum width of the panel.

2. In a wall bed, the combination with a panel turnable in an opening in a wall, said panel having vertical pivots which lie outside of the plane of the panel, said pivots including an upper plate secured to the upper edge of the wall opening and having a downwardly projecting off-set pintle, a corresponding socket plate on the panel to receive said pintle and the lower pivot comprising a pintle member secured to the lower edge of the panel and off-set to the same side of the panel that the upper pintle is, and in the same vertical plane with said upper pintle, and an adjustable floor socket for the lower pintle.

In testimony whereof I have hereunto set my hand in the presence of the subscribing witness.

NAPOLEON B. DOUGLASS.

Witness:

JOHN H. HERRING.
